FIG. 1

FIG. 2

FIG. 3

FIG. 4

FIG. 5

FIG. 6

FIG. 1 is a bottom perspective view of a framing module for lighting for ceilings or similar article showing our new design;

FIG. 2 is a cross-sectional view taken on line 2-2 of FIG. 1;

FIG. 3 is a cross-sectional view taken on line 3-3 of FIG. 2;

FIG. 4 is a bottom perspective view of an alternate embodiment of our new design;

FIG. 5 is a cross-sectional view taken on line 5-5 of FIG. 4; and

FIG. 6 is a cross-sectional view taken on line 6-6 of FIG. 4.

The dominant feature of our design resides in the parabolic shape of the side and end walls.

This is a continuation of design applications D. 386,168 and D. 386,169, both filed Aug. 6, 1973 and both now abandoned.

We claim:

The ornamental design for a framing module for lighting for ceilings or similar article, substantially as shown and described.
